ULTRAHIGH-FREQUENCY APPARATUS

George D. O'Neill, Port Washington, N. Y., assignor to Sylvania Electric Products Inc., a corporation of Massachusetts

Application March 13, 1948, Serial No. 14,807

14 Claims. (Cl. 250—36)

1

The present invention relates to radio circuits. In a useful form of high-frequency circuit, a planar-grid electron-discharge device is partly enclosed in a high-frequency resonator and a capacitor is interposed between the annular terminal of the planar grid and the resonator to block direct and low-frequency currents and to bypass the radio-frequency currents. The capacitor ordinarily takes the form of a dielectric annulus sandwiched between a metallic wall of the resonator and a metallic extension of the annular terminal.

Many difficulties are inherent in the foregoing arrangement. The capacitor is ordinarily designed to have a minimum impedance. This bypass, at its exterior edge, couples to space, so that, unfortunately, a part of the high-frequency power is unintentionally radiated, representing losses and uncontrolled local high-frequency fields. The path also provides coupling between moving bodies outside the resonator and its interior, resulting in variable reflections and operational instability.

One phase of the present invention aims at providing a novel construction for blocking direct-current and low-frequency signals and for connecting an annular-terminal vacuum tube to a high-frequency resonator, thereby minimizing one or more of the difficulties inherent in the comparable prior-art construction.

As to this phase of the invention it is proposed that an annular quarter-wave transmission line, having an open termination, be used, providing insulation circumferentially around the annular terminal of the vacuum tube at the input end of the line.

The outer end of the line, which is open to the surrounding space, may be said to terminate in a high impedance. Hereinafter I shall refer to this arrangement as an open termination, which results in a low value of input impedance when the physical construction is suitably adjusted to the signal frequency involved.

The term "annular transmission line" is intended to identify two-walled transmission lines wherein the input edges of the walls are spaced apart and close on themselves to constitute loops, and may take various forms, such as the cylindrical form of a coaxial line or the flat form of a radial line as more fully described below.

The bypass results obtained with this open quarter-wave annular line may be deficient for some purposes. The lower limit of the input impedance that is injected into the high-frequency circuit such as a resonator depends on the ap-

2

proach to perfect reflection at the open termination. Radiation losses and leakage may transform to a small but appreciable impedance at the input end of the open-ended quarter-wave line, and to reduce this effect is another object of this invention. An annular shorted quarter-wave line advantageously is joined circumferentially to a wall of the annular open-ended line adjacent the open termination. Its impedance is effectively in series with the high impedance of the open termination. At the frequency at which the open-ended line and the shorted line are effectively one-quarter wave-length long, the transformed impedance at the input end of the bypass is very nearly zero, whereas the direct-current insulation is unimpaired.

If the circuit is to be operated over a band of frequencies, the open line and the shorted line will not be equal to an electrical quarter wavelength for any except a single frequency. But if the open line is breached at a point near the open end by the input end of a first shorted annular quarter-wave line having maximum impedance at one frequency and again at a point very near the open end by a second annular shorted quarter-wave line having maximum impedance at a lower frequency, the impedance looking into the bypass will be low for a band of frequencies. The two shorted lines are effectively series-connected, and their impedances are added to the impedance of the open end of the nominally quarter-wave open line. This broad-banding of annular lines is another broad purpose of the invention.

The invention in its several aspects will be better understood from the following detailed description of various illustrative forms. In the drawings:

Fig. 1 is a longitudinal section of a cylindrically symmetrical combination of a planar-grid tube and a cavity resonator, showing the improved blocking or bypass construction, and Fig. 2 is an enlarged fragmentary view of that construction with a partial external view of the tube.

Fig. 3 is a diagrammatic view of a planar-grid tube-and-resonator combination, with a quarter-wave open annular line between the annular grid terminal and the resonator, and Figs. 4, 5, and 6 are like views of similar bypass arrangements improved by the addition of quarter-wave shorted annular lines.

Fig. 7 is a graphical aid to the proportioning of the radial quarter-wave lines forming part of some forms of this invention.

Figs. 8 and 9 are wiring diagrams of lumped-

constant analogies of two forms of radio frequency bypass constructions.

A simple embodiment of one phase of the invention is shown in Fig. 3. Resonator 10 is associated with a tube including a dynode or secondary-emitting anode 12, a positive planar grid 14, and a cathode 16, the interior metallic surface of resonator 10 being breached circumferentially about positive grid 14 at gap 17 filled with dielectric material. Output from resonator 10 is optionally obtained by loop 20 and guided along coaxial line 22 to the load. In accordance with one phase of the invention, the effective length of dielectric 18, sandwiched between two metal plates 24 and 26, is equal to an electrical quarter-wave when measured from the breach in the metallic surface of resonator 10 toward the outer edges of those plates 24, 26.

This combination of parts is diagrammatically shown in Fig. 8 with the direct-current circuit completed to constitute a dynatron oscillator of the type in my copending application, Serial No. 681,454 filed July 5, 1946. Dynode 12, positive grid 14, and cathode 16 form a vacuum tube (the envelope not being shown) which, when connected through choke Z to direct current power supply E and to the resonator represented by L, C, constitute the dynatron oscillator. The capacitor designated C represents total circuit shunt capacitance including that between electrodes 12 and 14 and for this reason it is shown dotted. The resonator circuit is completed, across the gap shown, by a quarter-wave line S which physically surrounds the annular terminal of the planar grid in the actual construction but which is represented by an open-circuit two-wire quarter-wave line. Dynode 12, a secondary emissive electrode, is connected to a tap in the direct-current supply through choke Z, the extremities of supply E being connected to positive grid 14 and to cathode 16. The secondary emission from dynode 12 promotes the functioning of the tube as part of the dynatron oscillator in the illustrative circuit, the operation of which is described in detail in my above-mentioned copending application.

It should be understood that the use of this tube and other tubes in combination with a resonator and the novel high frequency bypass arrangement is not limited to the generation of oscillations, but extends also to other applications such as modulation and amplification with circuits that will be obvious to those skilled in the art, including applications requiring more than one resonator. Furthermore, the physical arrangement of the annular open-ended quarter-wave line replacing the usual bypass capacitor is applicable to both positive- and negative-grid tubes, to diodes, and to multiple-grid tubes of the so-called planar grid type having an annular terminal for at least one grid.

From transmission line theory it will be understood that the impedance Z_i of line S at its input end is low where line S is made an electrical quarter-wave in length, and is terminated in a very high impedance at the other end, and is minimum with a termination of infinite impedance.

In order that the impedance Z_i may be held to a minimum for the mechanical arrangement shown in Fig. 3, consideration must be given to the material of the dielectric 18, the high-frequency conductivity of conducting plates 24 and 26, their distance apart, their inner and outer radii r_1 and r_2 respectively, and the resonant

wavelength λ of the cavity. The following discussion of wave-guide bypass design applies specifically to the radial form of Fig. 3, although the same general considerations are involved in a 5 cylindrical quarter-wave (coaxial) bypass in Figs. 5 and 6 and to other forms of quarter-wave bypass providing an insulating loop about an annular terminal of a tube or like device.

As previously indicated, an open quarter-wave 10 section to have minimum input impedance should have maximum impedance at the end from which the waves are reflected. Consequently, the bypass formed by conducting members 24 and 26, between which is preferably sandwiched the plate 15 18 of dielectric material such as polystyrene, are so dimensioned that the time required for a wave to travel from r_1 to r_2 is one quarter of the time of one cycle at average cavity frequency. 20 Considering the terminal impedance, by which is here meant the impedance an outward-traveling wave encounters at the periphery, of a lossless radial transmission line as being infinite, the input impedance is given by the relation

$$25 Z_i = -jZ_{0i} \frac{\cos(\theta_i - \Psi_L)}{\sin(\Psi_i - \Psi_L)} \quad (1)$$

where Z_{0i} is the surge impedance and the angles are defined by

$$30 \theta_i = \tan^{-1} \left[\frac{N_0(X_i)}{J_0(X_i)} \right] \quad (2)$$

$$35 \Psi_i = \tan^{-1} \left[\frac{J_1(X_i)}{-N_1(X_i)} \right] \quad (3)$$

$$3 \Psi_L = \tan^{-1} \left[\frac{J_1(X_L)}{-N_1(X_L)} \right] \quad (4)$$

When the dielectric medium 18, Fig. 3, is air,

$$40 X_i = 2\pi r_1 / \lambda$$

and

$$X_L = 2\pi r_2 / \lambda$$

for any other dielectric having a specific inductive capacity ϵ times greater than that of air, the value λ is inversely proportional to $\sqrt{\epsilon}$.

Since the input impedance Z_i is to be minimum, Equation 1 is set equal to zero; then

$$50 \cos(\theta_i - \Psi_L) = \pi/2$$

and it is seen that

$$55 \tan \theta_i = -\cot \Psi_L \quad (5)$$

Substitution by Equations 2 and 4 gives

$$55 \frac{N_0(X_i)}{J_0(X_i)} = \frac{N_1(X_L)}{J_1(X_L)} \quad (6)$$

In order to provide ready means for the solution of Equation 6 in the practical design of bypasses where the quarter-wave radial transmission line is used, I have constructed the curve, Fig. 7, which was obtained by assuming values of r_1/λ and obtaining $J_0(X_i)$ and $N_0(X_i)$ from tables of Bessel and Neumann functions. The 60 values of X_L corresponding to the values of X_i are then determined by finding the values of $N_1(X_L)/J_1(X_L)$ which correspond to the quotients $N_0(X_i)/J_0(X_i)$ and the results plotted as r_1/λ against r_2/λ as shown in Fig. 7, and as r_1/λ against $(r_2 - r_1)/\lambda$.

The curve, Fig. 7, is plotted with air dielectric. When the dielectric medium between plates of the radial line is some other material having a specific inductive capacity ϵ times greater than that of air, the value of λ is changed to λ' , which

is the wavelength in the new dielectric medium and which is expressed by the relation $\lambda' = \lambda/\sqrt{\epsilon}$.

It will be understood that practical limitations prevent full realization of the results predicted when only the foregoing ideal relations are considered. Three of these limitations of fundamental importance are:

1. Variations in electron tubes cause variations in the wavelength λ of the oscillations with the result that bypass dimensions may not be ideal for all tubes.

2. The terminating impedance of the radial transmission line can never be infinite, since the open-ended line couples into space.

3. No line is quite lossless due to surface resistance, dielectric losses and the like.

Thus, so far as the bypass is concerned, these limitations translated into Equation 1 show that the characteristic impedance Z_{01} is desirably held low, indicating the use of small spacing between the conducting members of the bypass and the use of a material having high dielectric constant. For the radial shorted line to be considered with Fig. 5, the reverse is true; i. e., separation of the conducting members is relatively great and air dielectric is preferred.

If a transverse electromagnetic wave is sent out between the inner surfaces of plates 24 and 26 from gap 17 adjacent grid 14, and reaches a point of infinite impedance at the radial extremity of the system, the wave is reflected back to the input gap and will then be 180° out of phase with the voltage by which it was excited, provided the dimensions of the conductors and the dielectric constant of the insulating material are properly related to the wavelength. To the extent that there are no losses in the dielectric medium or on the inner surfaces of plates 24 and 26, the exciting and fully-reflected voltages are equal in magnitude and, being 180° out of phase, mutually cancel and the system is said to have zero impedance. However, to the extent that the impedance of the termination is not infinite, the reactance of the bypass is greater than zero, so that energy is radiated. Just as the impedance of an antenna is a function not only of its dimensions but also of its surroundings, so the terminating impedance of the gap is affected by the surroundings and varies to some extent when surrounding objects are moved. These variations in terminating impedance are reflected back into the cavity as variations of the impedance into which the electron tube operates with resultant instability of developed power or frequency or both.

Fig. 4 illustrates one form of improvement over the open quarter-wave bypass shown in Fig. 3. In Fig. 4 there are shown the same resonator, output coupling, and tube, including a dynode, grid and cathode, as in Fig. 3. Replacing plates 24 and 26 in Fig. 3 are plates 28 and 30. A metal ring 32 is attached to plate 30, having two circular grooves 34 and 36. These grooves are of different depths, the shallower groove 34 being connected closer to input gap 38 than the other. The upper edge of ring 32 radially outward of grooves 34 and 36 provides two extensions 40 and 42 of the inner surface of plate 30. A layer of dielectric material 44 such as polystyrene separates plate 30 and ring 32 from plate 28 and the rest of the resonator.

A wave of a certain frequency travelling radially outward from gap 38 will have travelled one-quarter of a wavelength by the time it reaches groove 34. By making groove 34 effective as a

quarter-wave short-circuited line for that frequency, the open-ended terminal impedance of the arrangement in Fig. 3 would be increased for the arrangement in Fig. 4 by the effective impedance of the shorted quarterwave line. At the frequency for which the first groove is truly a quarter of a wave in electrical length, the bypass is terminated in a much higher impedance than was the case for Fig. 3, hence the impedance at gap 38, Fig. 4, is much lower.

For other frequencies than that for which groove is electrically one-quarter of a wavelength long and is connected to plate 30 one-quarter of a wavelength from input gap 38, groove 34 will present a high series impedance to an outwardly-travelling wave. The longer one 36 of the two grooves, connected further from gap 38 than groove 34, should preferably be made equal to one-quarter of a wave in electrical length for a lower frequency than that which matches groove 34. Groove 36 should be connected to the open-ended line bounded by plates 28 and 30 at a quarter wave distance from gap 38 for that lower frequency.

At frequencies between or slightly above or below the resonant frequencies of shorted coaxial lines 34 and 36, such lines are effectively reactances of less than maximum impedance, connected in series with each other and with the open termination of plates 28 and 30 as extended by surfaces 40 and 42. This arrangement preserves the insulating properties of the bypass but minimizes unintended radiation and coupling of the resonator to the surroundings. The analogous lumped-constant circuit is shown in Fig. 9, including the open quarter-wave annular line S' and the series annular reactors 34' and 36'. There is considerable reflection of the input wave by those reactors, and for this reason there is a considerable reduction in coupling to the exterior and in radiation through the bypass. The leakage fields are indicated by the dotted lines in Figs. 8 and 9 in a manner intended only to show their comparative strengths.

Referring to Fig. 4, the lengths of the two coaxial-line reactors depend upon the maximum and minimum wavelengths of the oscillations generated in the cavity. They are not, however, made one-fourth as long as these wavelengths, since this would result in a lowered performance at average wavelength than at the extremes. A good compromise is to make one reactor of electrical length L_1 such that it has maximum impedance at a wavelength γ_a which is intermediate between the average wavelength γ and the minimum wavelength $\gamma_{\min}$. Thus

$$L_1 = \frac{1}{4} \frac{(\lambda + \lambda_{\min})}{2} = \frac{\lambda + \lambda_{\min}}{8} = \frac{\lambda_a}{4}$$

Similarly

$$L_2 = \frac{\lambda + \lambda_{\max}}{8} = \frac{\lambda_b}{4}$$

It will be evident that if r_2' of Fig. 4 is computed for γ_a with the aid of the curve, Fig. 7, and the length of the innermost reactor also has an electrical length $\gamma_a/4$, the shunt impedance at gap 38, Fig. 4, is minimum when the wavelength is γ_a .

As a first approximation, r_2'' may be determined for γ_b using the curve if the series impedance offered by the short reactor to the long wavelength be ignored. This results in a solution for r_2'' which is too large. A rigorous solution is obtained by setting up the equation for

the input impedance of the gap 38 for wavelength λ_b with the impedance of the small reactor placed in series at the radius r_2' and setting this equal to zero. The solution for r_2'' is obtained graphically with the expenditure of more time than would ordinarily be warranted, since plots must be made from points determined from Bessel functions having small, closely-spaced arguments and hence by careful interpolation of the values given in such tables as those of Jähnke and Emde. However, solution of a few practical cases results in the conclusion that, when λ_a and λ_b differ from the average wavelength λ by approximately 5%, which represents ample spread, one may compute $r_2'' - r_1$ ignoring the short reactor, then use 95% of this figure in specifying r_2'' . It should be noted that such a relation cannot be strictly accurate since a rigorous solution must take full consideration of the surge impedances both of the by-pass and of the shorter reactor.

The broad-banding of the radial bypass is especially useful, with the dielectric shown, for cavities divided by insulation to provide for different direct-current potentials on the several electrodes of a tube; but the arrangement of multiple quarter-wave shorted lines on a common axis and encircling a quarter-wave open transmission line will be found useful in other high-frequency applications not involving direct-current insulation requirements.

Figs. 5 and 6 illustrate other arrangements of the open quarter-wave line completely surrounding the planar grid and multiple shorted quarter-wave lines adjacent the open termination of the open quarter-wave line. In Fig. 5 the open line comprises a pair of cylinders 46 and 48, the former being insulated from most of the resonator by dielectric spacer 50. Cylinder 48 does not extend to the open termination but is connected to disc 52, grooved to provide a shorted radial quarter-wave line 54 for maximum effectiveness at the shorter wavelength λ_a , and a somewhat longer short-circuited quarter-wave line 56, which corresponds to wavelength λ_b . In Fig. 6 the open line is similarly comprised of inner and outer metal cylinders 58 and 60 separated by an insulating passage 62, and, replacing radial series-connected shorted lines 54 and 56, is a first shorted quarter-wave line 64 within cylinder 58 and a second, somewhat longer, short-circuited quarter-wave line 66 outside cylinder 60. Lines 64 and 66 are folded back on the open quarter-wave line; all three lines may be filled with any suitable dielectric material. The use of a solid dielectric filler serves as a mechanical strengthener and in reducing the dimensions of the lines.

The radial quarter-wave reactors of Fig. 5 may have air as the dielectric in order that the surge impedance Z_{o1} be maximum. Taking the terminating impedance as zero, the input impedance as a lossless line will be

$$Z_i = jZ_{o1} \frac{\sin(\theta_i - \theta_L)}{\cos(\Psi_i - \theta_L)} \quad (7)$$

and is taken to be infinity when the distance from input to the short is electrically a quarter-wavelength. Hence the curves of Fig. 7 apply to the proportioning of radial reactors as to radial open quarter-wave lines. The wave-lengths λ_a and λ_b used in the design procedure are taken in the same manner as was explained for the case of Fig. 4 described above.

The system shown in Fig. 6 is more amenable to numerical solution than are those of Figs. 4

and 5. A more rigorous solution will be given as it illustrates the general method of attack on any of the systems discussed or which might be envisioned.

5 In order to avoid the need for considering the dielectric constant throughout the manipulations to follow, it may be considered unity—for air dielectric—and surge impedances and lengths will be recognized as varying inversely as the 10 square root of ϵ . Also, the conductance of the dielectric and resistance of the conductors may both be considered zero.

Certain mechanical and electrical dimensions are as follows:

- 15 λ =average wavelength
 $\lambda_{\min}$ =minimum useful wavelength generated in the resonator
 $\lambda_a = \frac{1}{2}(\lambda + \lambda_{\min})$
 $\lambda_{\max}$ =maximum useful wavelength generated
20 $\lambda_b = \frac{1}{2}(\lambda + \lambda_{\max})$
 L_0 =distance from the input gap to the first shorted quarter-wave line
 L_1 =length of the shorter quarter-wave shorted line
25 L_2 =length of the longer shorted quarter-wave line
 L_3 =length of the bypass (that is, the length from gap to the longer line)
 Z_{ob} =surge impedance of bypass
30 Z_{oc} =surge impedance of shorted lines
 $L_x = L_3 - L_0$

The impedance of the shorter line at a wavelength λ will be

$$35 Z_1 = jZ_{oc} \tan(2\pi L_1/\lambda) \quad (8)$$

where $Z_{oc} = 60 \ln(r_0/r_1)$ in which r_0 is the inside radius of the outer conductor and r_1 is the outside radius of the inner conductor.

40 Since Z_1 is to be infinite at wavelength λ_a , it is seen from (8) that this may be accomplished by making $L_1 = \lambda_a/4$. Similarly, the impedance of the longer shorted line is made infinite for λ_b by making $L_2 = \lambda_b/4$.

45 Consider the impedance at the gap for wavelength λ_a . Since it is terminated in an infinite impedance, we have:

$$Z = -jZ_{ob} \cot(2\pi L_0/\lambda_a) \quad (9)$$

where $Z_{ob} = 60 \ln(r_0/r_1)$, r_0 and r_1 this time referring to the conductors of the bypass. It is evident that if $Z=0$, then $L_0 = \lambda_a/4$.

Now for wavelength λ_b , the longer shorted line has a finite impedance which is inductive, and this is in series with a short additional length of line $L_x = L_3 - L_0$, which, being less than a quarter wavelength long and terminated in the infinite impedance of the second shorted line, is capacitive. The sum of these impedances we may designate as Z_a . Then, since $L_0 = \lambda_a/4$,

$$60 Z_a = jZ_{oc} \tan\left(\frac{\pi\lambda_a}{2\lambda_b}\right) - jZ_{ob} \cot\left(\frac{2\pi L_x}{\lambda_b}\right) \quad (10)$$

We may now set up another expression for Z_a by which (10) may be solved for L_x . An open-ended line of length $\lambda_b/4$ has zero input impedance at wavelength λ_b ; the impedance of a section of length $(\lambda_b/4 - L_0)$ also has the impedance Z_a , since in either case a line of length L_0 is terminated in the impedance Z_a . Then,

$$Z_a = -jZ_{ob} \cot\left[\frac{2\pi}{\lambda_b}\left(\frac{\lambda_b}{4} - L_0\right)\right] \\ = -jZ_{ob} \cot\left[\frac{\pi}{2\lambda_b}(\lambda_b - \lambda_a)\right] \\ = -jZ_{ob} \tan\left(\frac{\pi\lambda_a}{2\lambda_b}\right) \quad (11)$$

Eliminating Z_a between (10) and (11) and setting

$$L_x = L_3 - \lambda_a/4$$

yields

$$L_3 = \frac{\lambda_a}{4} + \text{arc cot} \left[\left(1 + \frac{Z_{oc}}{Z_{ob}} \right) \tan \left(\frac{\pi \lambda_a}{2 \lambda_b} \right) \right] \quad (12)$$

As an example, if $\lambda_a = 0.95\lambda$ and $\lambda_b = 1.05\lambda$, and $Z_{oc} = Z_{ob}$, $L_3 = 0.93\lambda_b/4$. In general, the surge impedance Z_{oc} of the shorted lines will be set higher than that of the bypass, Z_{ob} , and the result will be a somewhat lower value of L_3 .

It will be remembered that the system was described for air dielectric. For any other medium having dielectric constant ϵ , L_3 will be multiplied by

$$1/\sqrt{\epsilon}$$

It may be well to remark again that the corrections just described are ordinarily a second-order effect, and in those cases where a radial transmission line is part of the device, such as in Figs. 4 and 5, the correction may be approximated. The correction to the case where all coaxial lines are used is simple enough so that the more exact computation given by (12) is simple enough to warrant its use.

The several arrangements in Figs. 3 to 6 will find varied application depending on space and design factors. A further but particularly useful arrangement of the open quarter-wave line of Fig. 3, further modified to include multiple shorted quarter-wave lines as part of the termination of the open quarter-wave line is shown in Figs. 1 and 2. In Fig. 1, resonator 10' includes a rod 66 supporting dynode 12' adjacent positive planar grid 14'. Diaphragm 67 has a central portion threaded to support 66 and is joined to the walls of resonator 10' by threaded cap 69, this construction serving to facilitate assembly without stressing the glass unduly. Planar grid 14' is insulated from most of the resonator by a layer of dielectric material 68 such as polystyrene. Cathode 16' is supported below grid 14' and these three electrodes are enclosed in an evacuated envelope. The upper part of the envelope is in the form of a generally cylindrical or conical glass wall 70 the bottom of which is sealed to the annular extension corresponding to the usual terminal for a planar grid. The apex of the conical glass wall 70 is of somewhat thicker glass stock and provides a relatively long seal with support 66 of the dynode. This glass shape is well calculated to resist abrupt upward acceleration.

The planar grid terminal is extended downward to strengthen the seat for wall 70, and the metallic planar grid extension constitutes the axial wall 72 (see Fig. 2) of the lower part of the envelope. This extension constitutes one wall of the open quarter-wave line corresponding to plate 26 of Fig. 3, and the other plate of that open line is in the form of a complementary metal ring 74. The bottom of the envelope includes a formed metal annulus 76 fused to wall 72 and a glass exhaust tube portion 78 which also provides separate seals for the terminals of filamentary cathode 16' and for a getter-flashing lead that also serves as a direct-current lead for the grid. Annulus 76 and planar grid extension 72 constitute a shield substantially enclosing cathode 16'. Annulus 76 further extends the open quarter-wave line by providing a short radial bearing for dielectric ring 82. This is pressed by a composite

5 tube 84 which is threaded into ring 72 against the triode envelope which in turn is seated against polystyrene layer 68 within ring 74. Tube 84 includes a pair of shorted lines 86 and 88 adjacent the termination of the open line and provides a length of shielding for leads 80.

10 Of the form in Figs. 1 and 2 it will be noted that the open quarter-wave line may be other than radial or cylindrical as in Figs. 3-6; and in like sense the shorted quarter-wave lines at the open termination that impart broad-band effectiveness are similarly not necessarily confined to the flat radial or to the concentric cylindrical forms. The particular arrangement in Fig. 1, whereby the metallic portion of the tube envelope serves as one of the walls of the bypass, is claimed in copending application, Serial No. 14,726, filed March 13, 1948 of Paul Haas assigned to the assignee of this application.

15 Lines having lengths of any odd multiples of a quarter-wave may be substituted for the one-quarter wave lines described. Further detailed variations, as well as other applications of the novel subject matter in this case, will occur to 20 those skilled in the art; and for this reason I desire the appended claims to be broadly interpreted consistent with the spirit and scope of the invention.

25 What is claimed is:

30 1. In combination, a resonator having a conductive end wall, and a planar grid electron discharge device a grid of which has an annular terminal approximately in the plane of said wall, said terminal and said wall being separated by a high-frequency bypassing and direct-current blocking construction comprising an annular transmission line surrounding said terminal and extending externally of said resonator to an open 35 termination electrically one quarter of a wave length away from said terminal.

40 2. In combination, an electron-discharge device having a planar grid and another electrode the terminal of which is spaced from said planar grid, a resonator completing a high-frequency circuit between said electrode and said planar grid, and a quarter-wave transmission line surrounding said planar grid and insulating it from 45 said resonator, said line extending externally of said resonator and having an open termination.

50 3. The combination in claim 1 including a short-circuited annular transmission line one quarter of a wave in length breaching a wall of said transmission line adjacent said open termination.

55 4. The combination according to claim 1 including a pair of short-circuited annular transmission lines each circumferentially breaching a wall of said annular transmission line adjacent the open termination of said open transmission line, said short-circuited lines being of different effective lengths and being displaced from the 60 said planar grid terminal an electrical distance equal to their electrical lengths, respectively.

55 5. In combination a triode having a planar grid 65 between a cathode and a secondary emissive electrode arranged along an axis, said planar grid having an annular terminal, a metallic resonator connected between said terminal and said anode and enclosing the space between them, a circumferential breach between said grid terminal and said metallic resonator, and a two-walled transmission line having its walls insulated apart and connected to said terminal and to said resonator respectively but extending externally of said resonator, said line ending in an open termination

at a point electrically an odd multiple of quarter wavelengths from said breach.

6. In combination a high frequency circuit including an apertured conductive cavity, a device having multiple terminals at least one of which is annular and is set in the aperture of said cavity, an annular insulator encircling said annular terminal, and a pair of conductive walls at opposite surfaces of said insulator joined to said terminal and to said cavity at said aperture, said insulator and said conductive walls extending externally of said cavity and being dimensioned to constitute an open quarter-wave transmission line at the operative frequency of said circuit.

7. A high frequency circuit having a portion effective over a band of operating wavelengths, said portion including an annular transmission line having two conductive walls insulated apart, and closely adjoining series-connected shorted transmission lines each circumferentially breaching a wall of said annular transmission line respectively equal in length to one-quarter of different operating wavelengths in said band.

8. A high frequency circuit having a portion effective over a band of operating wavelengths, including a first two-walled transmission line having an annular terminal, and second and third annular transmission lines joined circumferentially each to a wall of said first line at distances from said terminal respectively equal to one-quarter of different wavelengths in said band and having maximum input impedance at said junction at said respective wavelengths.

9. A high frequency circuit having a broadband construction including an annular two-walled transmission line having an open termination and multiple annular short-circuited transmission lines of electrical lengths equalling a quarter of an operating wavelength at different points in said band joined circumferentially to said two-walled line adjacent and in series with said open termination.

10. A high frequency circuit having a broadband construction including an annular two-walled quarter-wave line having an open termination and multiple annular short-circuited transmission lines of electrical lengths equalling a quarter of an operating wavelength at different points in said band joined circumferentially to

said two-walled line adjacent and in series with said open termination.

5 11. A high frequency network including a two-walled annular transmission line having an input gap, a first short-circuited annular transmission line joined to said two-walled line circumferentially at a quarter-wave distance from said input gap at one frequency, and a second short-circuited annular transmission line joined to said two-walled line circumferentially at a quarter-wave distance from said gap at a second frequency.

10 12. A high frequency network including an annular quarter-wave transmission line having two walls insulated from each other and having an open termination, and a short-circuited quarter-wave line circumferentially joined to each wall of said open line adjacent and in series with said termination and connected in series with said open termination.

15 13. A high frequency network including an annular quarter-wave transmission line having two walls insulated from each other and having an open termination, and a short-circuited quarter-wave line circumferentially joined to a wall of said open line adjacent to and in series with said open termination.

20 14. A high frequency network including an annular transmission line having an input gap and an open termination in combination with a pair of short-circuited coaxial lines arranged one within the other breaching said annular line at distances from said gap electrically an odd multiple of quarter-waves from said gap at different frequencies, said short-circuited lines being odd multiples of quarter-waves in length at said different frequencies, respectively.
